COFFEE MAKER

Lee Wolfman, 437 Summit St.,
Englewood Cliffs, N.J. 07632

Filed Jan. 5, 1972, Ser. No. 215,698

Term of patent 14 years

Int. Cl. D7—02

U.S. Cl. D7—85

FIG. 1 is a perspective view of a coffee maker embodying my design;

FIG. 2 is a typical side view of the top portion insert of my coffee maker design, the bottom portion being omitted for the sake of clarity;

FIG. 3 is a top view of the insert shown in FIG. 2; and

FIG. 4 is a bottom view of the insert shown in FIG. 2. I claim:

The ornamental design for a coffee maker, substantially as shown and described.
